MYCOLOGY KIT

Raymond S. Michel, Portland, Oreg., assignor to United Medical Laboratories, Inc., Portland, Oreg., a corporation of Oregon

Filed Nov. 8, 1967, Ser. No. 9,325

Term of patent 14 years

(Cl. D83—1)

FIGURES 1 and 2 are interior plan views respectively of matching bottom and top pieces of the container, FIGURE 3 is a section as viewed along the line 3—3 of FIGURES 1 and 2 when the pieces shown therein are assembled in box-like formation, and

FIGURES 4 and 5 are exterior views on a reduced scale of the bottom and top pieces, shown respectively in FIGURES 1 and 2, when combined as a mailing case in the sectional form as shown in FIGURE 3.

I claim:

The ornamental design for a mycology kit, as shown and described.
